JUG OR SIMILAR ARTICLE

Harry Crisci, P.O. Box 231, New Castle, Pa. 16103

Filed Mar. 18, 1970, Ser. No. 21,950

Term of patent 14 years

Int. Cl. D9—01

U.S. Cl. D9—40

FIG. 1 is a top view of a jug or similar article showing my new design;

FIG. 2 is a rear elevational view thereof;

FIG. 3 is a side elevational view thereof; and

FIG. 4 is a sectional view taken along line 4—4 of FIG. 3.

The dominant features of my design reside in the neck substantially as shown and described.

I claim:

The ornamental design for a jug or similar article, substantially as shown and described.
